The ornamental design for a packaging for split-cup containers, as shown and described.

DESCRIPTION

FIG. 1 is a side perspective view of the assembled packaging for split-cup containers, in which the split-cup containers represented in stippled lines are part of the environment and form no part of the design;

FIG. 2 is a side view of the assembled packaging for split-cup containers; and,

FIG. 3 is a bottom perspective view of the assembled packaging for split-cup containers.
